UNITED STATES PATENT OFFICE

154,987

DESIGN FOR A RUSTIC VENETIAN BLIND

Noble Carroll, Barryton, Mich.

Application June 16, 1948, Serial No. 147,000

Term of patent 14 years

(Cl. D21—6)

To all whom it may concern:

Be it known that I, Noble Carroll, a citizen of the United States of America, residing at Barryton, in the county of Mecosta and State of Michigan, have invented a new, original, and ornamental Design for a Rustic Venetian Blind, of which the following is a specification, reference being had to the accompanying drawing, forming a part thereof, wherein:

I claim:

The ornamental design for a rustic Venetian blind, as shown.
